PROCESS FOR DRYING ORGANIC PHARMACEUTICALS

Sidney Beinfest, Berkeley Heights, Joseph Halpern, New Providence, Sidney Gister, Bound Brook, and Phillip Adams and Michael Zelkind, Berkeley Heights, N. J., assignors to Berkeley Chemical Corporation, Berkeley Heights, N. J., a corporation of New Jersey

Application November 20, 1957, Serial No. 697,529

6 Claims. (Cl. 34—15)

This invention relates to new and useful improvements in the obtaining of pharmaceuticals of high bulk density. More particularly it relates to a process of the nature indicated wherein these pharmaceuticals, after initial processing, are treated as a high concentration of solids in a heterogeneous system with a volatile liquid and at a controlled temperature above the melting point of the pharmaceuticals to ultimately provide the improved products.

Many normally solid organic pharmaceuticals in order to obtain the requisite purity after preparation are conventionally crystallized from volatile liquids, separated from most of the mother liquid by mechanical means, such as filtration or centrifugation, and then dried.

Their drying is done by standard means, e. g. using rotary kiln, atmospheric shelf, and vacuum shelf dryers. All these methods result in products of rather low bulk density, e. g., for 2-methyl-2-n-propyl propane 1,3 diol dicarbamate, a well known tranquilizer, 0.30 to 0.37 gms./cc. This in turn results in low flowability and consequent clumping in containers and hoppers. In addition as many of the crystals are electrostatic, dusting is a problem. These difficulties are particularly undesirable in pharmaceuticals because of difficulty in handling and potential hazards from exposure of pharmacologically active dusts.

These physical characteristics further lead to problems in tableting of the powders because of poor compressibility. Excessively large tablets are required for standard dosages and concomitant large packages. Because of these factors wet granulation has been necessary with consequent regrinding to improve flowability. These excipients are costly and tablet size is still larger than obtained by the process of this invention.

This invention provides an improved method of overcoming all these beforementioned difficulties. The method comprises crystallizing the pharmaceutical from a volatile liquid, separating and removing a major proportion of the liquid from the pharmaceutical-liquid system, to leave a high concentration of solid pharmaceutical product in a heterogeneous system with the residual volatile liquid, stripping off the remaining volatile liquid from the pharmaceutical, conveniently at a subatmospheric pressure, and at a temperature above the melting point of the pharmaceutical at the pressure utilized, but below its decomposition temperature, under which conditions the pharmaceutical is liquid, then cooling the pharmaceutical to solidify it and finally comminuting it to obtain the high bulk density product. Further details follow.

It is surprising to learn that in this manner the bulk density can be improved as much as 100%, e. g., for 2-methyl-2-n-propyl-propane, 1,3 diol dicarbamate from 0.35 to 0.7 gms./cc. after grinding. The flowability is increased and the need for wet granulation avoided. The dried material can be tabletted directly or granulations can be prepared by dry slugging. All these advantages are obtained with a reduction in drying time requirements. The tablets produced have a volume de-

2

crease of 25% or more for the same dosage as compared to tablets prepared from conventionally dried material.

The organic pharmaceuticals to which this invention is applicable are those that are normally solid (at conventional atmospheric conditions), have a decomposition temperature at least 10° C. above their melting points, and are capable of being purified by crystallization from a volatile liquid.

This invention is thus applicable to pharmaceuticals 10 of a wide variety of chemical structures, e. g., esters, amides, ethers, diols and polyols, acids, phenols, ketones, pyrimidines, etc. This invention is particularly suitable to the class of materials selected from the group consisting of alkanediols and alkanediol dicarbamates. Examples 15 of specific compounds to which this invention are applicable include butane 1,3 diol dicarbamate, 2-methyl-2-n-propyl-propane 1,3 diol dicarbamate, beta glucose pentacetate, carbromal, barbital, acetyl carbromal, thymol, lauric acid, diethyl stilboestrol, and mephenesin. 20 The volatile liquids from which the organic pharmaceuticals are crystallized or recrystallized are water or typical organic solvents and mixtures of the two. The organic volatile liquids thus include aliphatic and aromatic hydrocarbons, alcohols, esters, ketones, etc. and mixtures thereof. Specific examples include methanol and higher alcohols, benzene, toluene, xylene, carbon tetrachloride, naphtha, acetone, acetic acid, etc.

The actual crystallization procedure is no part of this invention and need not be elaborated upon here.

The major proportion of the volatile liquid is then removed from the solid pharmaceutical-volatile liquid system by mechanical separation such as centrifuging or filtration.

The removal of the major proportion of the volatile liquid leaves a high concentration of solid pharmaceutical in a heterogeneous system with the residual volatile liquid. The term "filter cake" is also utilized to connote this type system which normally has a liquid content of about 10 to 70 wt. percent.

40 The remaining volatile liquid is then stripped off from the pharmaceutical at a temperature above the melting point of the pharmaceutical at the pressure utilized, but below its decomposition temperature. The pressures can range from sub to superatmospheric depending upon the 45 solvent and temperature required. The pharmaceutical is thus liquid under these conditions. It is to be understood, of course, that the highly concentrated heterogeneous system can be heated to the desired controlled temperature prior to the application of the pressure 50 which is then utilized in the stripping operation. The temperatures given below refer to the terminal temperatures since in heating up the system it will of course have to go through the lower temperatures first. Finally the pressure utilized is easily chosen so as to permit the obtaining 55 of the desired temperature during the stripping operation which will permit melting but not decomposition. The exact temperature figures vary from each compound, e. g. butane 1,3 diol dicarbamate, the temperature utilized is in the range of about 152°—170° C. and for 2-methyl-2-n-propyl-propane 1,3 diol dicarbamate, it is in the range of about 107°—150° C. The figures can be determined for any given compound from its physical properties.

When subatmospheric pressures are employed they are 65 conveniently in the range of about 15 to 400 mm. Hg. Depending on the vapor pressure of the solvent, atmospheric or higher pressures may be required.

After the stripping operation the organic pharmaceutical is solidified by flaking, casting or chilling. The operations are conventional and need not be amplified herein. The solid is then comminuted as by grinding and

the high density product is obtained. It is to be understood that the term "commminuting" also includes previous processing steps that result in products of desired particle size, e. g. spray chilling or flaking.

The process of this invention is illustrated by the flow diagram. The remaining volatile liquid is stripped off from the filter cake in the kettle; the pharmaceutical is withdrawn through the valve and solidified as shown by flaking or casting.

This invention will be better understood by reference to the following examples of the treatment of the organic pharmaceutical according to the process of this invention.

Example 1.—Treatment of 2-methyl-2-n-propyl-propane 1,3 diol dicarbamate

A filter cake of 2-methyl-2-n-propyl-propane 1,3 diol dicarbamate crystallized from xylol was placed in a still and heated to 120° C., 15° above its true melting point, at which point it was completely liquid. The pressure was then reduced to a point at which the xylol distilled at a convenient rate, maintaining the temperature at 120°-130° C. by heating. As the solvent was removed, the pressure was reduced in order to maintain the rate of distillation until the pressure reached 15-20 mm. and the distillation ceased. The temperature was maintained throughout. The product was removed and cast in trays. After solidifying by cooling, the product was broken out and ground to the desired particle size in a hammer mill. The final product had a bulk density of 0.7 gms./cc. after 20 dried in an atmospheric shelf drier. The final product had all of the advantages listed before and none of the disadvantages of the control in further tabletting operations.

Example 2

Various other pharmaceuticals were treated in a similar manner as in Example 1. The details are presented below.

Pharmaceutical	Melting Point, °C.	Treatment Temp., °C.	Final Pressure, mm.	Solvent
Beta glucose pentaceta-	131-132	150	20	50 vol. percent H ₂ O, 50 vol. percent IPOH.
tato				
Carbromal	116-119	128	20	xylol.
Barbital	188-192	200	40	H ₂ O.
Acetyl carbromal	108-109	120	15	xylol.
Thymol	51	65	15	99 vol. percent IPOH.
Lauryl acid	44	100	15	50% IPOH, 50% H ₂ O.
Diethyl stilbesterol.	169-171	185	80	benzene.
Mephenesin	69-70	110	20	xylol.

In each case the final product obtained by treatment above its melting point had increased flowability and tabletting ease. The final bulk density can be varied according to particle size desired.

The advantages of this invention have been listed and others will be apparent to the skilled in the art. Fine organic pharmaceuticals of increased bulk density, which are more easily amenable to subsequent processing, are economically obtained. Since the solvents are distilled, they can be completely recovered by operating the condenser at a sufficiently low temperature. The process has resulted in very substantial manufacturing savings.

It can also be used where it is desired to screen or filter the melted liquid to remove foreign matter prior to chilling.

If desired, and preferably, final traces of volatile liquid can be removed from the stripped molten pharmaceutical prior to solidification, by blowing with an inert gas such as air, nitrogen or CO₂ under vacuum. Steam is particularly effective.

The process is advantageously applicable to materials having physiological properties, e. g. 4,7 dichloroquinoline, which as yet are not used as pharmaceuticals.

It is understood that this invention is not limited to the specific examples which have been offered merely as illustrations and that modifications may be made without departing from the spirit of the invention.

What is claimed is:

1. A process for drying an organic pharmaceutical, said organic pharmaceutical being normally solid and having a decomposition temperature at least 10° C. above its melting point and capable of being purified by crystallization from a volatile liquid, which comprises the steps of crystallizing the pharmaceutical from the volatile liquid; separating and removing a major proportion of the volatile liquid from the pharmaceutical-volatile liquid system to leave a high concentration of solid pharmaceutical in a heterogeneous system with the residual volatile liquid; stripping off remaining volatile liquid from the pharmaceutical at a temperature above the melting point of the pharmaceutical but below its decomposition temperature, at which temperature the pharmaceutical is liquid; cooling the stripped pharmaceutical to 20 solidify it and then comminuting it.
2. The process of claim 1 in which the stripping step is conducted at a subatmospheric pressure.
3. The process of claim 1 in which the volatile liquid is an organic liquid.
4. The process of claim 1 in which the volatile liquid is water.
5. The process of claim 1 in which the pharmaceutical is diethyl stilboestrol.
6. The process of claim 1 in which the pharmaceutical is mephenesin.
